MOTOR VEHICLE DOOR SYSTEM

Anton Rappl, Eggertsville, N. Y., assignor to Trico Products Corporation, Buffalo, N. Y.

Application June 14, 1947, Serial No. 754,672

6 Claims. (Cl. 268—66)

1

This invention relates to a motor vehicle and primarily to a mechanism for operating the door of the vehicle. It has heretofore been proposed to open and close the swinging door of an automobile by fluid pressure.

The present invention has for its object to provide an improved door actuating mechanism which is practical and efficient and insures the unlatching of the door prior to the operation of the door actuating motor.

A further object of the invention is to provide door actuating means wherein the door is controlled in its outward swinging as a factor of safety against injury to any person standing nearby.

The invention will further be found to reside in an improved power operated mechanism which will function independently of the usual hand control.

The foregoing and other objects will manifest themselves as the following description progresses, reference being had to the accompanying drawings wherein.

Fig. 1 is a diagrammatic lay-out illustrating the application of a door operated mechanism embodying the present invention;

Fig. 2 is a bottom plan view of the showing in Fig. 1;

Fig. 3 is an enlarged fragmentary sectional view through the door actuating motor;

Fig. 4 is a modified showing of the time delay unit for definitely insuring the motor actuation with respect to the door unlatching means; and

Fig. 5 is a similar view depicting a further modified time delay unit.

Referring more particularly to the drawings, the numeral 1 designates a door of the motor vehicle hinged at its forward edge by supporting means 2 and having a latch 3 on its rear edge operable by a handle 4 to enable the manual opening and closing of the door when such actuation is desired.

For power actuation of the door, the vehicle is provided with a motor, preferably of the fluid type and having a cylinder or chamber 6 and a piston 7, which latter term comprehends any fluid pressure responsive member. The motor may be pivotally mounted on the vehicle chassis 8, by a bracket 9, and have its piston rod 10 pivotally connected to an arm 12 of a rock shaft 13. A second arm 14 on the shaft has its free end slidably and pivotally engaged with a guide-way 15 on the bottom edge of the door. The fluid pressure differential for actuating the motor may be derived from a suitable source, such as

the intake manifold 16, to which latter the motor chamber is connected by the supply conduit 17. This conduit opens through branch passages 18, and the ports 19, 20 in the chamber heads 21 and 22, into the opposite ends of the chamber. A valve part 23 normally engages a seat 24 in each suction passage 18 to close off the suction communication and to vent the motor chamber to the atmosphere through a port 25. Consequently, the piston 7 normally will be atmospherically balanced by reason of the atmospheric vents at the opposite sides thereof. Filter pads 26 screen out foreign particles from entering the vents 25. An electro-magnet 27 is adapted to attract its armature 28 to unseat the valve part 23 and seat a second valve part 29 over the venting port 25 to close the latter. Therefore, in the attracted position the valve 23, 29, will close off the atmosphere from, and open the suction to, the motor. These valves at the opposite ends of the motor chamber are selectively controlled by a switch 30 which is accessibly located. When the valve is actuated the door will be swung accordingly.

Means are provided to retard the opening movement of the door and thereby prevent injury to any person standing alongside the vehicle and in the path of the swinging door. For this purpose the capacity of the port 19, or its associated passage 18, is restricted, as at 31, to throttle the evacuation of the air, from in advance of the piston. In order to avoid this retarding means functioning when the door is being power-closed a valve 32 is provided to bypass the restriction for freely admitting air behind the piston. For compactness, the door retarding port 31 may be formed in the valve 32 which is of disk shape. A spring 33 will act normally to close the valve over the port 19 so as to permit the valve opening for the free admission of atmospheric pressure to the trailing side of the piston when the door is being closed.

To facilitate the manual opening and closing of the door the two cylinder heads 21 and 22 are provided with pressure relieving ports 34 and 35 which are normally closed by valves 36 and 37 engaging the seats 38 and 39, respectively, under the urge of the springs 40 and 41. As the door is manually opened the piston will move to the right, as viewed in Fig. 3, and build up air pressure in advance of the piston to unseat the pressure relieving valve 37 against fluid resistance to the manual effort. Likewise, when the door is being manually closed, the valve 36 will unseat in response to the pressure in front

of the piston and relieve the same. Therefore, the door may be readily opened or closed manually without abnormal resistance being offered by the motor. However, when suction is applied to either side of the chamber the pressure differential will act to hold the forward pressure relieving valve to its seat.

For power actuation of the door the latch 3 will be power retracted automatically as by means of a relatively small motor having a chamber 42 and a piston 43. The piston rod 44 is connected to a latch retracting lever 45 by a play connection 46 which enables the manual retraction of the latch without moving the piston. Likewise the latch is connected to the handle 4 by a play connection 47 to avoid moving the handle when the latch is power actuated. These play connections readily permit a return spring 48 normally to project the latch to its operative position. The motor chamber 42 is connected to the suction supply line 17 by a conduit 49 so that whenever the door motor is operated the latch will also be retracted. The capacity of the conduit 49 is preferably larger than the door retarding port 31 to cause the latch to disengage before the door motor functions.

Means may be provided to positively insure the initial retraction of the latch before the door motor becomes effective. Fig. 4 illustrates, by way of example, such means wherein the latch releasing motor is, in effect, interposed in the pressure line leading to the door motor and associated with means to confine the pressure solely to the latch motor until the door is unlatched. To this end, an extension conduit 50 leads from the latch motor chamber 42 to the side of the door motor chamber to which the suction influence is applied when the door is to be opened, and interposed within this passage 50 is a check valve 51, which, when the latch motor chamber is connected to the suction line, will close upon its seat 52 and thereby confine the suction solely to the piston 43'. After the piston retracts the latch 3 from its keeper it will then function to establish interchamber communication. To this end the piston may carry a lug 53 which is designed to unseat the valve 51 after the latch reaches its retracted position, such valve unseating operation serving to open the suction line between the latch motor chamber and the door motor chamber. Thereafter, the door motor will become energized and open the door.

For closing the door, at which time the suction will be applied to the left hand side of the piston 7, as viewed in Fig. 3, the outside atmosphere will enter the door motor chamber at the right side of the piston through the circuitous path provided by the vent 25, Fig. 4, conduit 45', the latch motor chamber 42', the extended passage 50, and the motor port 13', for providing the required pressure differential for fluid actuation of the door piston 7. A spring 54 may be provided to unseat the valve 51.

In the modified embodiment of Fig. 5 a bowed spring leaf 55 is provided to assist the latch spring 48 in urging the latch to its operative position. In this embodiment the valve unseating lug 53' is carried by the valve 51' and is designed to protrude through an opening 56 in the spring 55 to be contacted by the descending piston 43'' when the suction influence is initially applied through the passage 49''. This action will serve to unseat the valve in a downward direction and against the action of the underlying spring 54'.

Should it become necessary to further retard the opening movement of the door the passage 18 may be throttled by rotatably adjusting the valve 57, as by means of a knob 58. A like control may also be provided for retarding the closing movement of the door, the valve 57 having its end face cut on a bias so as to progressively advance across the passage 18 to more or less fully restrict its capacity.

10 The door operator is practical in design and safe in operation. The opening movement of the door is controlled against violent bodily contact with anyone standing along the side of the vehicle. Obviously the door retarding means 31 could be arranged in the companion passage 19 for affecting the door closing movement if such is desired. The latch is always retracted prior to door movement so as to insure a practical and efficient accessory system for the motor vehicle.

20 While the foregoing description has been given in detail it is without thought of limitation since the inventive principles and teachings involved are capable of assuming other physical embodiments without departing from the spirit of the invention and the scope of the appended claims.

What is claimed is:

1. A door operator for motor vehicles, comprising a motor operatively connectible to the vehicle door for moving the same to and from a closed position, control means for said motor comprising interlock means normally preventing energization of said motor for door opening operation thereof, a latch normally holding the door in its closed position, and a second motor connected to the latch for rendering the latter inoperative, said second motor having a moving part having a normal position operatively corresponding to the normal operative position of said latch and an operating displacement through and beyond an intermediate position operatively corresponding to the inoperative position of said latch, said part being adapted and arranged to actuate said interlock means by and upon displacement thereof beyond said intermediate position for rendering the door motor operative subsequent to the unlatching of the door.

2. In a motor vehicle having an outwardly swinging door, a latch normally holding the door in its closed position, motor means operable initially to unlatch the door and then swing the door outwardly to an open position, manual means operable to retract the latch, said motor means comprising a fluid motor having a chamber with a piston slideable therein, retarding means providing restricted communication between one end of the chamber and a source of operating pressure to retard the opening movement of the door by said motor means, and independent means comprising a venting check valve communicating with one end of the chamber and opening in the direction of the fluid flow in said one end freeing the door of said retarding means for the manual opening of the door.

3. A door operator for motor vehicles, comprising a fluid motor operatively connected to a vehicle door for moving the same to and from a closed position, a latch normally holding the door in its closed position, a second fluid motor having moving means connected to the latch for rendering the same inoperative, said moving means having a normal position positively corresponding to the operative position of said latch and an operating travel through and beyond an intermediate position positively corresponding to

the inoperative position of said latch, conduit means connectable for operatively supplying the door motor with a flow of operating fluid pressure for opening movement of the door, and check valve means in said conduit means closing in the direction of said flow, said moving means being adapted and arranged to open said valve means by and upon travel of said moving means beyond said intermediate position.

4. In a motor vehicle having a movable door, a fluid motor connected to the door for moving the same back and forth, said motor having a piston slideable in a chamber, control valve means operable selectively to open the chamber at one side of the piston to a source of suction and to open the other side to the atmosphere for operating the motor by the pressure differential, and a venting check valve communicating between the atmosphere and one end of the chamber and opening outwardly therefrom and being responsive to super-atmospheric pressure for reducing the build-up of an abnormal pressure resistance to manual movement of the door.

5. In a motor vehicle having an outwardly swinging door, a fluid motor for swinging the door to and from its closed position, said motor having a chamber and a piston with passage means for selectively connecting either end of the chamber to a source of suction, a pressure relieving check valve communicating between the atmosphere and one end of the chamber and opening outwardly therefrom and responsive to super-atmospheric pressure to avoid the build-up of an abnormal pressure resistance to the manual operation of the door in one direction, and a flow restricting check valve in one passage means acting to restrict atmospheric communication to retard motor movement of the door in one direction and opening to freely admit atmospheric pressure in the opposite direction.

6. A door operator for motor vehicles comprising a suction motor operatively connected to a vehicle door for moving the same to and from a closed position, a latch normally holding the door in its closed position, a second suction motor having moving means connected to the latch for rendering the same inoperative, said moving means having a normal position positively corresponding to the operative position of said latch and an operative travel through and beyond an intermediate position positively corresponding to the inoperative position of said latch, conduit means including control means connected to the door motor for operatively supplying the door motor with an operating suction for door opening movement, normally closed valve means in said conduit means, said moving means being adapted and arranged to open said valve means by and upon travel of said moving means beyond said intermediate position, and check valve means connected to the door motor in parallel with said conduit means and opening outwardly to the atmosphere.
